UNITED STATES PATENT OFFICE.

CATHARINE A. GRISWOLD, OF NEW YORK, N. Y.

DESIGN FOR THE ORNAMENTATION OF CORSETS.

SPECIFICATION forming part of Design No. 19,238, dated July 30, 1889.

Application filed June 29, 1889. Serial No. 316,098. Term of patent 14 years.

To all whom it may concern:

Be it known that I, CATHARINE A. GRISWOLD, of the city, county, and State of New York, a citizen of the United States, have 5 invented and produced a new and original Design for the Ornamentation of Corsets, of which the following is a full, clear, and exact description, reference being had to the accompanying drawing, forming part of this specification.

The single figure in the drawing represents in side elevation a corset containing my invention.

The leading and special feature of my new 15 design consists in bands or stripes, each of which is curved or bent upon itself about midway its ends and the ends of each of which are approximately rectilinear in direction and converge toward each other at their free extremitie, said bands or stripes thus shaped 20 extending in a series along the upper edge of the corset and reaching longitudinally downwardly from said upper edge toward the waist-line of the corset.

25 A represents a corset, which may be in the usual and ordinary form.

B B' B² represent bands or stripes, each one

of which has a curve or bend b upon itself about midway its ends, as shown, the said ends b' and b² of each said band or stripe being approximately rectilinear in direction and converging toward each other at their free extremities, as shown. The bands or stripes B B' B² thus shaped extend in a series along the upper edge of the corset in succession, as 30 35 shown, and reach longitudinally from said upper edge downwardly toward the waist-line of the corset, as shown.

What I claim is—

The design for the ornamentation of a corset 40 herein described and shown, the same consisting in bands or stripes B B' B², each of which has a curve or bend b upon itself about midway its ends, and said ends b' and b² of which are approximately rectilinear in direction and 45 converge toward each other at their free extremities, said bands or stripes thus shaped extending in a series along the upper edge of the corset and reaching downwardly from said upper edge toward the waist-line of the corset. 50

CATHARINE A. GRISWOLD.
